SOUND-FINDER

Rudi W. Mandl, New York, N. Y.

Application October 6, 1937, Serial No. 167,637

4 Claims. (Cl. 181—26)

This invention relates to a sound finder, preferably used for selecting and collecting sound coming from a predetermined region or direction and concentrating it on and against a sound responsive receiver controlling an electric device. 5 The finder is a box, open at one end, having sound absorbing wall portions and properly shaped sound reflecting wall portions directing the selected sound to the receiver positioned at 10 a suitable point within the box.

Sound finders of this general character so far proposed have either their direction selectivity restricted to short sound waves, that is to high notes, or they require a very excessive bulk and extension. 15 Furthermore, with these finders of the prior art, the focus is on the same side of the reflector as the sound source, and hence the receiver obstructs and shatters the incoming sound waves. This results also in an unsatisfactory arrangement of the apparatus: it becomes even more bulky, and the apparatus may become unsuitable, for instance, for simultaneously taking photographic pictures and sound records of an actor. Furthermore, with these known finders, the focus is indistinctly determined for the 20 reception of long sound waves, and hence the selectivity with respect to these becomes imperfect.

The present invention eliminates all these disadvantages. It is accordingly the object of the 30 present invention, to provide for a relatively compact sound finder which is source selective through the entire range of audible sound waves, having a sharp selectivity with respect to said 35 whole range, a finder with the receiver located off the direction of the incoming sound.

All these advantages are obtained by the use 40 of a strip shaped reflector. In principle, the reflecting wall portion has the shape of a portion of an ellipsoid of revolution, which term "ellipsoid" and "ellipse" will include in this specification and in the claims a paraboloid or a parabola respectively as a special case, the parabola being considered as an ellipse of infinite eccentricity. 45 The longitudinal extension of the strip is on a meridian of the ellipsoid, the width is on a zone of the ellipsoid. However, for practical purposes, it is sufficient and preferred, to suppress the curvature crosswise the longitudinal extension 50 of the strip. The reflector assumes accordingly the shape of a portion of an elliptical cylinder, the strip being cut out at right angles to the mantle lines of the same. It is furthermore characteristic for my reflector that the elliptical arc along the longitudinal extension of my strip-

shaped reflector is not symmetric with respect to the major principal axis of the ellipse, but it is unsymmetric thereto. In the preferred embodiment, the strip is cut out on one side of the major axis, so that it does not contain the apex point at the end of the major axis, and it extends about equally to both sides of that point of the ellipse at which the tangent forms an angle of 45 degrees with the two principal axes of the ellipse. 10

These and other advantages and characteristics of the present invention will now be described in the specification, and a preferred embodiment will be illustrated in the drawing, it being understood that, since the principles of 15 my invention can be incorporated in many specific devices, it is not intended to be limited to the ones here shown, except as such limitations are clearly imposed by the appended claims.

In the drawing, like numerals refer to similar 20 parts throughout the several views, of which

Fig. 1 represents an ordinarily horizontal cross section on line 1—1 of Fig. 2 through the sound box of a sound finder incorporating my invention,

Fig. 2 represents an elevational view of the 25 finder seen from the line 2—2 of Fig. 1,

Fig. 3 is a diagram illustrating the shape of the reflecting wall portion of the sound box,

Fig. 4 is a perspective view of the sound finder illustrating the use of a periscope or telescope 30 for focussing the sound source,

Fig. 5 shows in a larger scale the preferred receiver used within the sound finder.

In Figs. 1 and 2, there is represented a sound box broadly designated by 10, supported by and 35 rotatably fixed to a standard 11, the same having adjustable feet 12 for tilting it, and a hand-wheel 13 for turning it about a vertical axis. The sound box 10 has a plane sound absorbing bottom 15 and top 14, made of or covered by felt 40 or the like. Box 10 is open at 16, and has a substantially elliptically bent sound reflector 17 made of smooth hard material, such as wood or metal, and sound absorbing side walls 18 and 19. The latter comprise a grating 20 composed of narrow strips of metal or canvas, backed by a wall 21 of sound deadening material such as felt or cork. 22 represents a microphone receiver broadly.

Top 14 and bottom 15 are preferably parallel 50 and spaced about 1 foot apart. In Fig. 3, the shape of reflector 17 is illustrated. The surface of 17 is substantially a cylinder over a segment of an elliptical line, 31 representing the entire ellipse. I use only the portion 17 of the ellipse 55

situated between and spaced from the apex or end of the major axis 32 and the end of the minor axis 33, said portion preferably including the point 34 of the ellipse, the tangent AB of which forms an angle of 45 degrees with the major axis through the foci 22' and 35, and hence also with the minor axis of the ellipse. The receiver 22 is located adjacent one focus of the ellipse, and is exposed to the sound waves emanating from the other focus 35. In practice, the eccentricity from 22 to 35 is rather long, and the ellipse approaches the shape of a parabola.

The sound absorbing side wall portions 18, 19 form a broken line, the inner boundaries following straight lines connecting the foci with the end points of the reflector 17. At the ends of the opening 16, reflector flanges 23 are provided for increasing the selectivity of the finder.

Fig. 4 illustrates the use of the finder. During the taking of a sound picture, (for instance), periscope 41 rigidly fastened to the finder box 10 is directed towards the source of the sound intended for recordation. The box is accordingly turned by the hand wheel 18, and, if necessary, it may be tilted by the use of the adjustable screws 12. Turning only will generally be sufficient. The reflector 17 of the box has to be about 10 feet large, if the selectivity shall include all sound waves of the audible range. It becomes somewhat smaller if the deepest notes are dispensed with. The recording device will then preferably be made unresponsive to such deep notes.

Fig. 5 illustrates the receiver used. It is peculiar by its flattened or compressed mouth piece 71, which opens in a slot 72. This extends at right angles to top and bottom 15 and 16, and practically all the way from top to bottom. It may be desirable to use a mouth piece 71 with a hinged door member 73 fastened to the stationary portion thereof. Door 73 may be turned by any means, not shown, whereby the selectivity of the device will be changed.

I claim:

1. A mobile sound finder box having a pair of substantially plane and parallel side walls, a pronouncedly elongated strip-shaped sound reflecting wall in its crosswise direction substantially straight and at right angles to said side walls and following in its lengthwise extension the contour of an elliptic arc connecting a first point of

an ellipse spaced from the apex thereof with a second point spaced farther thereof, and a sound sensitive electric receiver within the box adjacent the focus of said elliptic arc.

2. A mobile sound finder box having a pair of substantially plane and parallel side walls, a pronouncedly elongated strip-shaped sound reflecting wall in its crosswise direction substantially straight and at right angles to said side walls and following in its lengthwise extension the contour of an elliptic arc connecting a first point of an ellipse spaced from the apex thereof with a second point spaced farther thereof, said arc being inclined under 45 degrees towards the principal axes of the ellipse at one of its points, and a sound sensitive electric receiver within the box adjacent the focus of said elliptic arc.

3. A mobile sound finder box having a pair of substantially plane and parallel side walls, a pronouncedly elongated strip-shaped sound reflecting wall in its crosswise direction substantially straight and at right angles to said side walls and following in its lengthwise extension the contour of an elliptic arc connecting a first point of an ellipse spaced from the apex thereof with a second point spaced farther thereof, said arc being inclined under 45 degrees towards the principal axes of the ellipse at one of its points near its center, and a sound sensitive electric receiver within the box adjacent the focus of said elliptic arc.

4. A sound finder box having a plane top wall, a plane bottom wall parallel to said top wall, a sound reflecting side wall at right angles to said top and bottom following through a distance substantially longer than the distance between said top and bottom the contour of an elliptic arc connecting a first point spaced from the apex of the generating ellipse with a second point spaced farther from said apex and being inclined at one of its points under 45 degrees towards the principal axes of said ellipse, plane sound absorbing walls at right angles to said top and bottom following three straight lines connecting the foci of said ellipse with the ends of said elliptic arc, the box being open along a fourth line of said kind, and a sound sensitive receiver within the box adjacent the focus of said ellipse; whereby sound produced at the external focus of the ellipse is selected and concentrated at the receiver.
